Specification for Design.

Patented Feb. 17, 1920.

Application filed April 30, 1919. Serial No. 293,848. Term of patent 14 years.

To all whom it may concern:

Be it known that I, CHARLES M. WOLCOTT, a citizen of the United States, residing at Baltimore city, State of Maryland, have invented a new, original, and ornamental Design for a Rubber Tread Portion for Shoes, of which the following is a specification, reference being had to the accompanying drawings, forming a part hereof.

In the drawings Figure 1 is a longitudinal section on line X—X of Fig. 2, and Fig. 2 is

a plan view of a shoe heel and sole, showing my new design.

I claim:

The ornamental design for a rubber tread portion for shoes, as shown.

In testimony whereof I affix my signature in the presence of two witnesses.

CHARLES M. WOLCOTT.
